[57] CLAIM

The ornamental design for a cigarette lighter, as shown and described.

DESCRIPTION

FIG. 1 is a perspective view of the cigarette lighter embodying my new design;
FIG. 2 is a front elevational view thereof;
FIG. 3 is a top plan view thereof;
FIG. 4 is a bottom view thereof;
FIG. 5 is a side elevational view thereof;
FIG. 6 is a rear elevational view thereof.
The cigarette lighter is shaded to indicate contrast.
